Patented Aug. 20, 1918.

UNITED STATES PATENT OFFICE.

SWAN O. WIDELL, OF ROCKFORD, ILLINOIS.

GATE.

1,276,602.

Specification of Letters Patent. Patented Aug. 20, 1918.

Application filed October 5, 1917. Serial No. 194,868.

To all whom it may concern:

Be it known that I, SWAN O. WIDELL, a citizen of the United States, residing at Rockford, in the county of Winnebago and 5 State of Illinois, have invented certain new and useful Improvements in Gates, of which the following is a specification.

This invention relates in general to gates especially adapted as a fence gate for farm 10 usage, although equally well adapted to serve as a gate or closure in other places.

In the present instance, I have aimed, primarily to provide a gate of simple and improved construction, characterized mainly 15 by the provision of a novel form of hinge mounting and suspension means, by which the gate is capable of being opened by either a sliding lengthwise movement as upon a trackway or by swinging movement similar 20 to the ordinary hinge gate movement. This provision enables my improved gate to be well adapted to practically any condition and requirement of usage which may arise.

A further object of my invention is to 25 provide a gate mounting of the character described, constructed in a very simple, yet substantial manner so that the cost of production will be comparatively low and the mounting will be practical and durable for 30 the purpose desired.

The construction and operation of my 35 improvements will be better understood and appreciated by reference to the following description when considered in connection with the accompanying drawings, in which—

Figure 1 is a front elevation of a fence gate, closed, embodying my improvements;

Fig. 2 is a vertical sectional view taken on 40 the line 2—2 of Fig. 1;

Fig. 3 is an enlarged plan view of the hinged end of the gate and showing in dotted lines the latter swung to an open position; and

Fig. 4 is a plan sectional view taken substantially on the line 4—4 of Fig. 1.

While my improvements pertain essentially to the mounting of a gate, I have illustrated a preferred construction of the 50 gate, *per se*, although in this connection, it should be noted that the gate might be suitably constructed as long as it may be adapted for use with my improved mounting. In the instance illustrated, fixed gate posts A

and B define the sides of the passageway to be closed by the gate. The gate, designated generally by reference character 5, in the present instance consists of upper and lower rails 6 and 7 in the form of ordinary metal pipes which are rigidly joined together by the end rails 8 and 9 and intermediate rail 11, suitable wire fabric or the like 12 forming the body of the gate. I prefer to rigidly secure the pipes 6 and 7 to the end rails 8 and 9 by means of specially constructed brackets 13, which are shaped to receive both the upright and horizontal rails, as shown, and are bolted thereto. The brackets 13 secured to the upright gate end 8, are provided with apertured extensions 14 adapted to engage the ordinary pintles of a gate post, in case it should be desired to use the gate on an ordinary hinge mounting.

The gate supporting means is designed so that the gate may be opened and closed either by sliding it lengthwise upon a trackway or by swinging the gate upon a pintle or hinge mounting, or by opening it partially by both methods. The mounting includes a roller 15 upon which the upper rail or pipe 6 rests and is adapted to roll. This roller serves as a permanent means for suspending the gate, and the gate may be slid lengthwise thereon to the left, viewing Fig. 1, to an open position. The roller in turn is mounted so as to turn bodily on an upright axis or pintle about which the gate may be swung horizontally, as upon a hinged mounting. The mounting for the roller and the means for attachment thereof

to the pintle or pivot bolt I have in the present instance formed in two parts, consisting generally of brackets 16 and 17, both embracing the sides of and rigidly secured to an upright bar or post 18, the bracket 16 being equipped with a stud 19 upon which the roller is revolubly mounted and the bracket 17 being equipped with a horizontal portion 21 pivotally connected by means of a pintel or pivot bolt 22 to a bracket 23 in turn

fixedly secured to the post A, said horizontal portion having an upright portion 24 serving as an outer support for the stud 19 and as a guide to retain the roller in operative position on the stud. Thus, it will be seen that the roller is mounted so as to turn about an upright axis. The bar 18 connects the roller and hinge gate mount-

ing just described with a lower hinge mounting coaxial with the upper hinge and consisting of the hinge elements 25 and 26 connected by a pintle 27 and respectively secured to the bar 18 and post A. The bar 18 serves to properly sustain the roller 15 and to hold it against displacement or tilting movement, by reason of its lower hinge connection, when the gate is being swung about the hinge mounting. The construction of the brackets 16 and 17 and the mounting of the supporting roller in the manner described permits the desired objects to be obtained in a very simple and practical manner and also enables a mounting of this character to be sold as an attachment to be applied to any ordinary fence gate having an upper rail, whether wood or metal, corresponding to the top rail 6, which should in this connection be adapted to slide upon the roller. The use of my improvements with the ordinary farm gate will be obvious, since most gates are provided with a top rail adapted to slide on the roller mounting which I have provided. By using my improvements the gate is entirely suspended from the top rail and by reason of the mounting of the latter upon the roller in the manner described the gate may be very easily slid back and forth, and when opened is in a balanced condition, which further facilitates moving the gate. Thus, a quite heavy gate may be comparatively easily opened by first sliding it lengthwise to a partially opened position in which the weight of the gate is balanced on the roller support and then by swinging the gate on its hinged mounting to fully open the passageway. Any suitable locking means, latch or the like, might be employed at the free end of the gate to hold it in connection with the post B when the gate is closed, and in the present instance, arms 28 secured to the end rail 9 are adapted to

enter openings in the post B by lengthwise movement of the gate.

It is believed that the foregoing conveys a clear understanding of the construction and operation of my improvements, and it should be understood that while I have illustrated one working embodiment thereof, changes in details of construction and arrangement of parts might be resorted to without departing from the spirit and scope of the invention as expressed in the appended claim.

I claim:

Means for mounting a sliding and swinging gate comprising in combination with a post and a gate having a horizontal slide rail, upper and lower pintle brackets secured to the post, an upright roller-hanger attached at its lower end through the agency of a pintle to the lower pintle bracket, a bracket secured to the upper portion of said roller-hanger having a horizontal portion resting on the upper pintle bracket, a pintle in alinement with the lower pintle and connecting said horizontal portion of the hanger pintle bracket with the upper post pintle bracket, said horizontal portion of the hanger pintle bracket having its end adjacent to the post turned upwardly to provide a support for one end of a roller supporting pin, a bracket secured to the roller hanger and provided with a horizontal roller pin disposed in substantially vertical alinement with and above the upper pintle and supported at its outer end in the upright portion of the hanger pintle bracket, and a roller mounted on said pin between the pin supporting bracket and the upright portion of the pintle bracket and adapted to receive said horizontal rail of the gate so that the gate may slide lengthwise on the roller and swing laterally about the axis of the pintles.

SWAN O. WIDELL.
